(57) **CLAIM**

The ornamental design for a handheld vacuum, as shown and described.

DESCRIPTION

FIG. 1 is a top view of a handheld vacuum showing our new design.

FIG. 2 is a left side view thereof.

FIG. 3 is a bottom view thereof.

FIG. 4 is a right side view thereof.

FIG. 5 is a rear view thereof.

FIG. 6 is a front view thereof; and,

FIG. 7 is a perspective view thereof.

The broken lines shown depict portions of the handheld vacuum that form no part of the claimed design.
